UNITED STATES PATENT OFFICE.

CHRISTIAN AALBORG, OF PITTSBURGH, PENNSYLVANIA.

VACUUM SWEEPER.

Application filed July 20, 1923. Serial No. 652,684.

My invention relates to suction sweepers, and it has special relation to sweepers of the portable type.

One object of the invention is to provide a portable, bagless, suction sweeper.

Another object of the invention is to provide a suction sweeper in which the current of air is circulated continuously in one substantially close path.

Another object of the invention is to provide a power-operated suction sweeper of the above-indicated character having the air cleaning devices disposed entirely within the casing of the sweeper.

A further object of the invention is to provide a suction sweeper with a dust receptacle positioned within the casing of the sweeper and detachable therefrom.

A still further object of the invention is to provide a novel construction of filter to which dust and lint does not adhere and which cannot become clogged.

In the illustrated embodiment of my invention, a fan draws air through a suction nozzle into a casing and forces it through a convex filter made of wire screen superimposed upon a layer of fiber cloth. The air is then forced through a discharge nozzle adjacent to the suction nozzle. A rotating brush is located in the discharge nozzle.

In the accompanying drawings,

Fig. 1 is a top plan view of a suction sweeper embodying the invention, parts being broken away to facilitate illustration;

Fig. 2 is a vertical sectional view of the suction sweeper showing the motor housing or dome in side elevation;

Fig. 3 is a transverse section on the line III-III of Fig. 1;

Fig. 4 is a fragmentary plan view of the closure disc and the adjacent portion of the hood showing partition walls partly in section;

Fig. 5 is a detail of a bearing for the brush;

Figs. 6 and 7 are detail views of parts of the brush control mechanism;

Fig. 8 is a detail view of a device for supporting and adjusting the position of a gear housing;

Fig. 9 is a detail of a latch and cooperating parts for securing the pair to the hood;

Figs. 10, 11, 12 and 13 are detail views of the brush-driving mechanism and control means therefor;

Fig. 14 is a top plan view of the dust pan removed from the casing;

Fig. 15 is an end elevational view of the pan;

Fig. 16 is a side elevational view of the pan; and

Fig. 17 is a view in vertical longitudinal section through the pan.

Referring to Figs. 1 and 2, a hood 10, a pan 11 and a dome 12 constitute a casing for housing the operating parts of a suction sweeper, the assembly being such that a low casing may be used, that is to say, low with respect to the large stationary types of vacuum cleaners. The hood is substantially rectangular in plan view and is supported by rollers 5, each mounted for rotation within a corner of the hood. The bottom of the hood terminates in an edge lying almost in a horizontal plane. The top wall 13 of the hood is somewhat flat but merges, by gradual curves, with the side walls. The front wall 14 extends downwardly to a point immediately adjacent to the surface on which the rollers 5 travel in the cleaning operation, and is formed at its end into a lip 15, spaced slightly from a partition 16, which extends upwardly and interiorly of the hood substantially parallel with the front wall 14 to form a suction nozzle.

The side walls 17 and 18 of the hood 10 are formed integral with the front wall 14 and the partition 16 and together therewith constitute an intake chamber 20. Where front wall 14 merges with top wall 13 the partition 116 is correspondingly curved but spaced from the front wall to provide room for a sufficient volume of incoming air. The partition 16 extends rearwardly for a considerable distance, the intake compartment being bounded on the sides by vertical walls 21 and 22 which converge from the front corners of the hood 10 to points centrally thereof. In this area, the intake chamber is restricted to a comparatively narrow 100

throat 23, formed by top wall 13, vertical partition walls 24 and 25 and bottom wall 26. The bottom wall 26 has a longitudinal opening 27 therein closed by a plate 28 secured in position by screws 29, directed into the bottom wall.

5 A pair of cup-like extensions 30 are formed at the front corners of the hood, extending laterally therefrom, thus broadening 10 ing the suction nozzle.

15 A brush compartment 31 is provided immediately rearwardly of partition 16 for the reception of a pair of axially aligned brushes 32 and 33. The outer end of brush 33 is received in a ferrule 136 from which projects a stud 137 that is journaled in a bearing 34. The outer end of brush 32 is received in a ferrule 138, from which a stud 139 projects journaled in a bearing 35.

20 On one side of the axis of the brush, a short screw 140 is threaded in bearing 35 from which it extends upwardly until it engages a lug 141 depending from the hood 10, as best shown in Fig. 5. The bearing 35 25 has an opening therein, forwardly of the axis of the brush, in which a long screw 142 is slidably fitted, the screw being threaded in a lug 143. By giving the long screw 142 a left hand turn and then giving short screw 30 140 a right hand turn, the bearing 35 may be lowered. By reversing the adjustments 35 of the screws, 142 and 140 the bearing 35 may be raised thus varying the vertical position of the brush. A finger 144 on the bearing 35 engages lug 143 and limits the upward adjustment of the bearing. The bearing 34 is similar in construction and adjustment.

40 A ferrule 36 receives the inner end of brush 33 to which it is rigidly connected. A sleeve 37 projects inwardly from the ferrule 36 and is secured by a pin 38 to a stud 39 on a spiral gear 40. The spiral gear 40 is housed in a trough 41 provided with an 45 end closure 42 which serves as a bearing for stud 39. Brush 32 is operatively connected to the spiral gear 40 by a ferrule 145, a sleeve 146 thereon, a pin 147 and a stud 148 rigid with the spiral gear 40 and journaled 50 in the trough 41 as a bearing. Spiral gear 40 meshes with spiral gear 43, rigid with short shaft 44 mounted for rotation in a horizontal housing 45 which at its front end is formed into an enlargement 46 closed by 55 a cap 47. Cap 47 prevents forward movement of shaft 44.

60 The housing 45 is integral with trough 41, which depends therefrom. A horizontal lug 149 is formed on the front of the trough 65 and has smooth openings 150 and 151 therein and a tapped opening 152 best shown in Fig. 8. A screw 153 is received in opening 152 and rests at its upper end against an abutment 154 extending inwardly from 65 front wall 14 of the hood. Screws 155 and

156 are received in openings 150 and 151 respectively, and are threaded into abutment 154. By loosening screws 155 and 156 and tightening screws 153, the lug 149 is secured in a lowered position. The lug may be secured in raised position in an obvious manner.

70 A partition 157 separates the throat 23 from the brush compartment 31 and is provided with a slot, same to receive the housing 45. Packing 158 between enlargement 46 and partition 157 seals throat 23 from the brush compartment 31.

75 Short shaft 44 is formed into a female clutch member 48, adapted to receive a male 80 clutch member 49 on a long shaft section 50. The shaft section 50 is formed into an annular rack 51 with which pinion 52 meshes.

85 The pinion 52 is rotatable in a bearing 53, formed on the housing 45, and has a race 54 thereon for receiving the end of a screw 55 threaded through the bearing to prevent movement of the pinion in the direction of its axis. The pinion projects at its other end beyond bearing 53, and carries 90 a disc 56 having an arm 57 thereon, provided at its end with two spaced upwardly directed flanges 58 and 60 (Figs. 6 and 7). A finger 61 downwardly directed from a leaf spring 62 is received between the 95 flanges, and leaf spring 62 is carried by a stud 63 projecting through an opening in a depending support 64 on closure disc 65 (Fig. 3). The lower face of the support 64 has stops 66 and 67 thereon for limiting 100 the movement of plate 62 which is controlled manually by means of a knurled knob 68 from which the stud 63 depends.

105 The top wall 13 of the hood 10 has a circular opening therein bounded by an annular shoulder 70 on which closure disc 65 rests. A shoulder 71 is provided on closure disc 65 and rests against shoulder 70. Fastening plates 72 and 73 retain the closure disc in position.

110 Slots 74 and 75 are provided in the top wall 13 to permit the assembling of the disc which is accomplished by inserting finger 61 between flanges 58 and 60 moving plates 72 and 73 through slots 74 and 75 and rotating 115 the closure disc to place the plates 72 and 73 beneath the shoulder 70.

120 The shaft section 50 carries a worm gear 80 at its rear end, the horizontal housing 45 being enlarged to form a chamber 81 for the reception of the worm gear. A cap 82 is threaded in the rear end of the housing. The worm gear 80 is spaced forwardly on the chamber 81 and the compartment is of such size as to permit rearward movement 125 of the worm gear to a position wherein it is out of engagement with a worm 83 with which it normally meshes.

130 The longitudinal housing 45 has a cup 84, formed thereon for the reception of the

lower end of worm 83, which holds the worm in mesh with worm wheel 80.

Worm 83 is formed on a drive shaft 85 rotated by the motor 86, which is enclosed by dome 12. The shaft 85 is journaled for rotation in a bearing 87 on a bell-shaped bearing bracket 88 having a plurality of openings 90 therein for the admission of air to cool the motor.

10 A bell-shaped fan 91 is threaded on worm 83 and is secured thereto by a screw 92. The bell shape of the fan and of the bearing bracket is such as to permit the motor 86 to be positioned immediately adjacent to the

15 fan 91, room for bearing 87 between the fan and the motor, being provided by the central recess in the fan resulting from its bell-like shape. The fan 91 carries a plurality of blades 93, downwardly directed therefrom.

20 The hood 10 is substantially flat but carries an extension 94 having an opening therein for receiving a shoulder 95 on the dome 12. A flange 96 outwardly directed from the dome 12 rests on the edge of the hood so that

25 the shoulder and the flange cooperate with the edge of the hood. Screws 97 retain the dome 12 in position. Screws 98 are also provided for securing bracket 88 to dome 12.

A handle 100, bifurcated to form arms 101 30 which extend on opposite sides of dome 12, is pivoted to the hood. The handle is provided with electrical terminals constructed as illustrated and described in my Patent No. 1,576,701 issued March 16, 1926.

35 The hood 10 is provided with an inwardly, rearwardly and downwardly directed flange 102, which overlies the throat 23 and is disposed immediately below the fan 91.

Bottom wall 26, is provided also with a 40 downwardly and rearwardly directed flange 103, which is spaced forwardly a slight distance from the rear wall 104, of the hood. A tubular support 105 is formed on the bottom wall 26 and receives pin 106 to hold lug 107

45 rigidly in position on the tubular support. The lug 107 is integral with cup 84, so that the longitudinal housing 45 is, at its lower end, rigid with the hood.

The pan 11 is substantially flat and is provided with longitudinal flanges 110 and 111 50 and a transverse flange 112 (Figs. 15, 16 and 17). The flanges rest against a shoulder 113 formed adjacent the lower edge of the hood 10. Suitable packing 114 is interposed 55 between the flanges and the shoulder. A depending lip 115 is provided on the hood downwardly directed from the shoulder.

The pan 11 is cut away at the lower corners so as to fit into the hood 10 inwardly 60 of the rollers 5 provided at these places. A longitudinal upwardly extending rib 116 is formed on the pan 11 and spaced inwardly from flange 110. A similar rib 117 is spaced inwardly of rib 116 and is of greater height 65 than rib 116. Spaced from 117 is a rib 118

of substantially the same height as rib 116.

A central rib 120 is provided which is still lower than rib 118. Ribs 121, 122 and 123 are spaced in series from rib 120, being substantially equal in height to ribs 116, 117 70 and 118. Stretched over the pan 11 and secured to flanges 110, 111 and 112 is a sheet 124 of fiber cloth upon which a wire screen 125 is superimposed. The fiber sheet and wire screen constitute an air filter and are 75 maintained in position by means of screws 126 extending into the flanges and ribs of the pan.

Between flanges 110 and rib 120, the filter is bulged by reason of the height of rib 117. 80 Each of the ribs 116, 117, 118, 120, 121, 122 and 123 is peaked centrally and inclining downwardly towards its end. The shape of each of the ribs tends further to impart a bulge to the filter centrally of each of the two 85 areas of the filter between rib 120 and flanges 110 and 111. As rib 120 is low, the filter is relatively flat notwithstanding the bulges therein. This arrangement makes for compactness. 90

The pan 11 is formed into a downwardly and forwardly directed lip 127 positioned immediately adjacent to the brush 32 the arrangement constituting a discharge nozzle. 95 Adjacent to the nozzle is a transverse partition 128 (Fig. 1) which is one of the walls defining the brush compartment 31.

A strip of rubber 129 is disposed in a recess 130 in each of the ribs and extends transversely of the entire pan being secured thereto and contacting on its upper surface with the partition 128 and also passing transversely of and in engagement with bottom wall 26 of throat 23. 100

Pan 11 is detachably secured to the hood 10 by a pair of latches, shown in detail of Fig. 9. Each latch comprises a hook 160 formed on the pan, a lever 161 pivoted on the hood, and a wire loop 162 running through an opening in the lever and extending over the hook as the pivot point of the lever is exterior of a line running between the points of contact of the loop with the hood and the lever the tendency of the loop to contract retains the latch in operative position. 105 110 115

In the operation of the device, the sweeper is pushed over the surface to be cleaned, by means of handle 100, and dust is drawn by the fan 91 through the suction nozzle into the intake compartment 20, whence it passes 120 into the restricted throat 23. In the travel of the air through this distance it does not encounter any of the operative parts of the device.

From the throat 23, the air is drawn rearwardly and is then forced downwardly beyond flange 103 and near the rear wall 104 of the hood 10. The rotation of the fan causes an air circulation through the apertures 90 in the bearing support 88 for cool- 125 130

ing of the motor 86. The rotation of shaft 85 also operates, through worm 83 and worm gear 80, to rotate the longitudinal shaft comprising sections 44 and 50, and spiral gears 13 to drive the brushes 32 and 33.

At times, it may be desirable to disconnect the brushes when only suction action is desired. The brushes may be disconnected from the motor by turning knurled knob 68, 10 manually, to move leaf spring 62 and finger 61. Engagement of the finger 61 with flanges 60 on arm 57 of disc 56 results in the turning of pinion 52 which operates on rack 51 to move shaft section 50 rearwardly, 15 thereby sliding male clutch member 49 from female clutch member 48 but not disengaging the clutch members. In the retracted position of shaft section 50, power is not transmitted to the brush 32 as the worm gear 80 is out of mesh with the worm 83. If desired, closure disc 65 may then be removed from top wall 13 of the hood and an auxiliary suction device which is disclosed in my copending application Serial No. 719,703 20 filed June 13, 1924 may be secured in the opening.

After the air passes the fan 91, it is forced downwardly, as described, adjacent to the lower wall 104 of the hood 10 and spreads 25 out over the filter. The dust encounters the wire screen of the filter and is separated thereby from the air, the cleaned air passing forwardly among the ribs of the pan. The dust and lint are not in immediate contact 30 with the fiber cloth but rest upon the wire screen from which they are more easily removed as they do not adhere as tenaciously to the metal. The dust and lint is not disposed between the wire screen and the sheet 35 of fiber cloth as the ribs support the cloth in intimate contact with the screen and impart a convex shape to the filter. The fiber cloth is not permitted at any place to sag below the wire screen.

40 The pan 11 does not communicate with throat 23 at any point except adjacent to fan 91 and flange 103 whereby the air is forced outwardly from the pan in a purified condition because of the action of the filter.

45 The brush 32 is in the path of travel of the discharged air which removes the lint and dirt therefrom. The dirt removed from the brush is not permitted to escape from the casing but is forced forwardly by the air 50 passing beyond the discharge nozzle 127 and into the suction nozzle, thus creating a continuous circulation of air through the machine.

55 The dirt and dust removed from the air is deposited on the filter which has a large substantially horizontal area and considerable capacity so that it does not readily become clogged. The rib 120 being lower than the adjacent ribs divides the filter into 60 two convex portions. Making the rib 120

relatively low does not militate against the advantageous functioning of the convex arrangement of the filter but tends to further conserve space and renders the device more compact since there is economy of room that 70 would be taken up if the rib 120 were of greater altitude.

The pan 11 may be readily detached from the hood, as described above, to permit dust and dirt to be removed from the filter and 75 pan, which is replaced in the hood when cleaned.

The flatness of the hood and casing facilitates the utilization of the sweeper in comparatively inaccessible places and the cup-like extensions 30 may be readily inserted 80 into corners.

The invention may be embodied in other constructions than that illustrated and described and extensively modified. A substantial range of equivalents is contemplated within the scope of the appended claims.

I claim as my invention:

1. In a suction cleaner, the combination of a casing having a suction opening and a discharge opening therein and adapted for movement over an article to be cleaned, means for drawing air through said suction opening and discharging it through said discharge opening, a sheet of fiber cloth, a wire screen contiguous to said fiber cloth, said fiber cloth and said screen being disposed in the path of travel of the air, and means for retaining said cloth contiguous to said screen irrespective of the action of the air. 90

2. In a suction cleaner, the combination of a casing having a suction opening and a discharge opening therein and adapted for movement over an article to be cleaned, means for drawing air through said suction opening and forcing it through said discharge opening, a sheet of fiber material, a wire screen thereabove contiguous thereto, and means supporting said material and said screen in the path of travel of the air and with the central portion of the material and screen bulged upwardly on the side towards which the air approaches. 100

3. In a suction cleaner, the combination of a casing having an opening therein and adapted for movement over an article to be cleaned, means for drawing air through said opening, a pan serving as a lower portion of said casing, a sheet of fiber cloth, a wire screen superimposed upon said sheet, means supporting said sheet and screen in the path of travel of the air with the wire screen disposed on the side of said sheet from which the air approaches, and ribs on said pan supporting said sheet and said screen and extending in the direction from which a r 110 approaches said sheet and said wire screen. 120

4. In a suction cleaner, the combination of a casing having an opening therein and adapted for movement over an article to be 130

cleaned, means for drawing air through said opening, a sheet of fiber material, a wire screen contiguous to said sheet, means supporting said sheet and said wire screen in the path of travel of the air, a pan serving as the lower portion of said casing on the lower side thereof, and ribs on said pan higher in their central portions than at their ends and imparting a bulge to said sheet and said screen in the direction from which the air approaches said screen.

5. A suction cleaner comprising in combination a casing having one wall shaped to

serve as a front, said casing being provided with a suction opening located near the front 15 of the casing and a discharge opening, means for circulating air through the openings, a brush disposed in the rear of the suction opening to cooperate with the air circulating means in cleaning operations and means 20 for cleansing the air as it passes from the suction opening to the discharge opening.

In testimony whereof, I have hereunto subscribed my name this 12th day of July, 1923.

CHRISTIAN AALBORG.
